UNITED STATES PATENT OFFICE

152,121

DESIGN FOR A COIN HEAD

John W. Nimitz, also known as John W. Nimtz,
Chicago, Ill., assignor to Raymond T. Moloney,
Chicago, Ill.

Application February 6, 1947, Serial No. 136,720

Term of patent 14 years

(Cl. D52—3)

To all whom it may concern:

Be it known that I, John W. Nimitz, also known as John W. Nimtz, a citizen of the United States and resident of Chicago, Cook County, State of Illinois, have invented a new, original, and ornamental Design for a Coin Head, of which the following is a specification, reference being had to the accompanying drawing, forming a part thereof.

Fig. 1 is a top plan view of a coin head, embodying my new design;

Fig. 2 is a front elevational view of the same;

Fig. 3 is a side elevation of the same.

The back of the coin head is substantially without ornamentation.

I claim:

The ornamental design for a coin head, as shown and described.

JOHN W. NIMITZ,

Also Known as John W. Nimtz.
